PASTEBOARD BOX

Russell Chally, Morris, Ill.

Application December 27, 1937, Serial No. 181,876

2 Claims. (Cl. 229—31)

The primary object of this invention resides in the provision of a pasteboard box of such construction that certain operations usually practiced in manufacturing boxes of this character are obviated so as to increase output there-of with the minimum amount of labor.

A further object of this invention relates to a box formed of pasteboard or the like, the general object of the invention being to provide a box that can be manufactured very cheaply, so that it can be sold at small cost and one which can be shipped or stored in flat knocked-down condition and set up in the minimum length of time for use.

A further object of the invention is to make the box either with a separate closure or one that is formed with the box.

This invention also consists in certain other features of construction, combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Fig. 1 is a perspective view of the box and closure.

Fig. 2 is a sectional view approximately on line 2—2 of Fig. 1.

Fig. 3 is a sectional view approximately on line 3—3 of Fig. 1.

Fig. 4 is a sectional view through a corner portion of the box.

Fig. 5 is a view of the box and its closure in flat or knocked-down condition.

Fig. 6 is a detail view showing a folded corner of the box.

Fig. 7 is a view of a blank for forming either a box or its closure, where the box is separate from the closure.

Fig. 8 is a transverse section through the box and closure in separated condition.

In these drawings, the box is shown at A and the lid or closure at B, and in that form of the invention shown in Figs. 1 to 6, the box and lid are formed from a single piece of suitable material. In these views, the box includes the bottom 1, the sides 2 and the ends 3, the ends and sides being separated from the bottom by the lines 4, which lines form the small corner pieces 5 that are located between the extremities of the end and side parts. Each corner piece has

a scored or fold line 6 passing diagonally there-through. A flap 7 is formed on the outer end 3 and is separated therefrom by a line 8 and this flap has a dove-tail shaped extension 9 on an intermediate part of its outer edge. The center 5 part of the flap is also cut to form a tongue 10 which is of substantially T shape.

The closure or lid B is composed of the top 11, which has one side edge provided with a score or fold line 12 between the inner end part 10 of the box and closure, and said lid also includes the sides 13, which are separated from the adjacent corner parts of the box by slits 14. The lid also includes the one end 15, formed by the line 16 and the corner parts 17 formed by the lines 15 18, which separate the ends from the top, and the line 16. These corner parts also have diagonal lines 19 therein and the end 15 has the flap 20 separated therefrom by the line 21 and said flap has an extension of dove-tail configuration thereon as shown at 22.

The top adjacent the end 15, has the two substantially U-shaped slits 23 therein for receiving the ends of the tongue 10 when the lid is to be fastened to the box as shown in Fig. 1. 25

In manufacturing the box constructed as aforesaid for shipment to the trade in knocked-down condition the flaps 7 and 20 are folded upon the ends 3 and 15 respectively and retained in such position by glueing the extensions 9 and 22 together with the medial portions of the aforesaid flaps to their associated ends whereupon those portions of the flaps extending in opposite directions from the medial glued and reinforced areas form pockets for the reception of 35 the folded corners 5 and 17 when the box and closure are set up for use.

Upon setting the box and closure up for use the sides thereof are folded on the score lines 4 and 18 respectively at which time the corners 40 5 and 17 are folded upon themselves and tucked under the unglued portions of the flaps 7 and 20 and, through the instrumentality of the medial glued areas of the ends, the corners will not become dislodged without reversing the setting up operation.

In order to fasten the lid in closed position on the box, it is swung over into the box and the ends of the tongue 10 seated in the slits 23, as shown in Figs. 1, 2 and 3. 50

In the modification shown in Figs. 7 and 8, both the box and the detached lid, are formed from similar blanks, one of which is shown at A' in Fig. 7. As shown in this view, the blank includes the main part 25, the sides 26 and the ends 55

27 and the corner parts 28 at the intersections of the sides and ends. All of these parts have score or fold lines defining them, as heretofore set forth. However, in this form of the invention the flaps 29 are formed with small dove-tail shaped extensions 30 at its center which together with the medial portions of the flaps are glued to the end part to form pockets on opposite sides thereof, as shown in Fig. 8, the setting-up operation being similar to the first form of the invention, excepting the box and lid are separate. Fig. 8 shows how the lid is disposed over the box before placing the two parts together.

Thus it will be seen that I have provided a simple form of box structure and one that can be manufactured to sell at low cost and one that can be quickly and easily set up.

It is thought from the foregoing description that the advantages and novel features of the invention will be readily apparent.

It is to be understood that changes may be made in the construction, combination and arrangement of the several parts, provided such changes fall within the scope of the appended claims.

Having thus described my invention what I claim and desire to protect by Letters Patent is:

1. A box element having an end wall and side walls and corner portions formed integral with adjoining ends of the side and end walls, said end wall being of increased width and projecting outwardly beyond the side walls and midway its length having an outwardly projecting tongue spaced from ends of the end wall a distance appreciably greater than the width of the corner

portions, the end wall being folded inwardly along a line flush with edges of said corner portions to dispose the outer side edge of said tongue even with the inner margin of the end wall, said tongue being fixedly secured against the inner face of the end wall in face to face engagement therewith and the inwardly folded portions of the end wall between the tongue and ends of the wall being free to provide elongated flaps spaced from the inner edge of the end wall and of appreciably greater length than the width of the corner portions, said corner portions being folded inwardly along diagonally extending lines against end portions of the end wall and tucked under the flaps to removably secure the folded corner portions and hold the side and end walls in a set up position.

2. A folding box section comprising a bottom wall, side and end walls formed on the bottom wall, foldable corner flaps connecting the side and end walls together, a locking flap formed on an end wall and extending the full length thereof and being of substantially one half the width of said end wall, said flap being foldable over the inner face of the end wall, a fastening extension formed on the central part of the locking flap and extending a substantial distance beyond the middle of the end wall, an adhesive securing the extension only to the inner face of the end wall, and the length of the portions of said locking flap on each side of said extension being substantially greater than the overall width of said corner flap.

RUSSELL CHALLY. 35
